[57] ABSTRACT

An integrating analog-to-digital converter comprising: an analog input signal source, first and second analog reference signal sources, integrating means common to the analog input signal source and the first and second analog reference signal sources, a first analog reference signal from the first analog reference signal

source having such a polarity as to increase the integrated output from the integrating means in a positive direction in accordance with the supply of the first analog reference signal to the integrating means and the second analog reference signal from the second analog reference signal source being opposite in polarity to the first analog reference signal, a clock pulse source, a pulse counter, means for supplying the integrating means with an analog input signal from the analog input signal source in a predetermined analog input signal integrating time period determined by a clock pulse from the clock pulse source, means for supplying the integrating means with the second analog reference signal or the first analog reference signal according as the integrated output is positive or negative at the time of completion of the integration of the analog input signal by the integrating means in a first one of n 's reference signal integrating time periods sequentially following the analog input signal integrating time period and determined by the clock pulse, (n being an integer more than 2 and the j th analog reference signal integrating time period being $1/(j-1)$ times the first one and $j = 2, 3, \dots, n$), means for supplying the integrating means with the second analog reference signal or the first analog reference signal according as the integrated output at the time of termination of the $(j-1)$ th analog reference signal integrating time period is positive or negative, and means for supplying the pulse counter with the clock pulse from the clock pulse source in the j th analog reference signal integrating time period when the integrated output from the integrating means at the time of completion of integration of the analog input signal is positive (or negative) and when the integrated output from the integrating means is positive (or negative) at the time of termination of the $(j-1)$ th analog reference signal integrating time period.

INTEGRATING ANALOG-TO-DIGITAL CONVERTER

BACKGROUND OF THE INVENTION

1. Field of the Invention

This invention relates to an integrating analog-to-digital converter adapted such that valve of an analog input signal integrated for a predetermined period of time is converted into a digital valve.

2. Description of the Prior Art

In conventional types of analog-to-digital converters an analog input signal is integrated and a digital output corresponding to the level of the analog input signal is produced based on the integrated output. However, the conventional converters are constructed on the assumption that no change occurs in the level and/or polarity of the analog input signal in the integration thereof. Accordingly, these prior converters cannot be used in the case where some changes are expected to occur in the level and/or polarity of the analog input signal during its integration.

SUMMARY OF THE INVENTION

One object of this invention is to provide an analog-to-digital converter which is adapted to obtain a digital output in accordance with a valve of the analog input signal integrated for a predetermined period of time. The analog-to-digital converter of this invention can be used irrespective of a change in the level and/or polarity of the analog input signal during its integration. In the analog-to-digital converter of this invention a digital output is provided in accordance with the level of the analog input signal when no change occurs in the level and/or polarity of the analog input signal during its integration.

Another object of this invention is to provide a analog-to-digital converter which is designed to produce a digital output of a valve proportional to a valve of an analog input signal integrated for a predetermined period of time.

Another object of this invention is to provide an analog-to-digital converter which is adapted to produce a digital output of a valve corresponding to a valve of an analog input signal integrated for a predetermined period of time best corrected in accordance with the integrated valve.

Still another object of this invention is to provide an analog-to-digital converter which is adapted to produce a digital output of a valve of an analog input signal integrated for a predetermined period of time such that the relation between the integrated value of the analog input signal and the digital output is obtained with a broken line characteristic.

Other objects, features and advantages of this invention will become apparent from the following description taken in conjunction with the accompanying drawings.

BRIEF DESCRIPTION OF THE DRAWINGS

FIG. 1 is a block diagram showing an example of an integrating analog-to-digital converter according to this invention;

Figs. 2A to 2G are a series of signal waveform diagrams, for explaining the examples of FIGS. 1 and 4;

FIG. 3 is a graph showing the relationship of the number of pulses counted to an analog input voltage; and

FIG. 4 is a block diagram illustrating a modified form of the integrating analog-to-digital converter according to this invention.

DESCRIPTION OF THE PREFERRED EMBODIMENTS

FIG. 1 illustrates one example of this invention. In the figure, reference numeral 1 indicates an analog input signal source, from which an analog input voltage V_I is supplied to an input terminal 4 of an integration circuit 3 through a fixed contact a and a movable contact c of a change-over switch 2. The integration circuit 3 includes an amplifier 5, an integrating resistor 6 and an integrating capacitor 7 and the amplifier 5 is connected at input side to the input terminal 4 through the integrating resistor 6 and at output side to the input side thereof through the integrating capacitor 7 constituting the so-called Miller integrator construction. An output terminal 8 of the integration circuit 3 is connected to the output side of the amplifier 5 and a reset switch 9 is connected between the input and output sides of the amplifier 5.

Reference numerals 10P and 10N designate first and second analog reference signal sources, respectively. A positive reference voltage $+V_P$ of a constant level is supplied from the one signal source 10P to the input terminal 4 of the integration circuit through fixed and movable contacts a and c of a change-over switch 11 and a fixed contact b and the movable contact c of the change-over switch 2. While, a negative reference voltage $-V_N$ of a constant level is supplied from the other signal source 10N to the input terminal 4 of the integration circuit 3 through a fixed contact b and the movable contact c of the change-over switch 11 and the fixed and movable contacts b and c of the changeover switch 2. In this case, the voltages $+V_P$ and $-V_N$ are selected to bear a relationship $|+V_P| = |-V_N|$ therebetween.

An integrated output E derived from the output terminal 8 is fed to a comparator circuit 12 which utilizes zero voltage as the reference and is adapted to provide a compared output Q of binary indication which provides an indication "1" when the integrated output E is positive or zero and "0" when the output E is negative. The compared output Q is fed to terminals d of D-type flip-flop circuits 13 and 14.

Reference numeral 15 indicates a clock pulse source, from which a clock pulse train CP0 of a period T_1 such as shown in FIG. 2A is supplied to a waveform shaping circuit 16 to derive therefrom a clock pulse CP1 such as depicted in FIG. 2B which is produced at the time corresponding to the leading edge of each pulse of the pulse train CP0. The clock pulse CP1 thus obtained is applied to an input terminal 18 of a timing signal generator circuit 17, which has output terminals 19, 20, 21, 22, 23 and 24. Let it be assumed that the pulses of the pulse train CP1 are sequentially produced at times t_0 , t_1 , t_2 , $\dots$. The timing signal generator circuit 17 is adapted to derive a rectangular wave R1 for timing use such as shown in FIG. 2C from the output terminal 19, a pulse train P1 such as shown in FIG. 2D from the output terminal 20, a rectangular wave R2 such as shown in FIG. 2E from the output terminal 21, a pulse P2 such as shown in FIG. 2F from the output terminal 22, a reset pulse P3 such as shown in FIG. 2G from the out-

put terminal 23, and a reset pulse P4 such as shown in FIG. 2H from the output terminal 24. The rectangular wave R1 for timing use is such as depicted in FIG. 2C which has a value "1" of the binary indication for periods of time represented by $32\tau_1 = T_C$ between the times t_0 and t_{32} , between t_{64} and t_{96} , between t_{128} and t_{160} , . . . and a value "0" for the other remaining period and has a period T_0 represented by $64\tau_1 = 2T_C$. The pulse train P1 is such as depicted in FIG. 2D which consists of pulses produced at the times t_{32} , t_{48} , t_{56} , t_{60} , t_{62} , t_{63} , t_{96} , t_{112} , t_{120} , t_{124} , t_{126} , t_{127} , . . . and having the period T_0 , respectively. The rectangular wave R2 for timing use is such as depicted in FIG. 2E which as a value "1" of the binary indication for periods from t_{48} to t_{64} , t_{112} to t_{128} , . . . and a value "0" for the other remaining periods of time and has the period T_0 . The pulse P2 is such as depicted in FIG. 2F which is produced at the times t_{32} , t_{96} , . . . and has the period T_0 . The reset pulse P3 is such as depicted in FIG. 2G which is produced at the times t_{47} , t_{111} , . . ., respectively, and has the period T_0 . The reset pulse P4 is such as depicted in FIG. 2H which has the value "1" of the binary indication for periods of time from t_{63} to t_{64} , t_{127} to t_{128} , . . . and the value "0" for the other remaining periods of time and has the period T_0 . If a first period between first and second pulses of the pulse train P1 is taken as the reference T_1 , the time of second, third, fourth and fifth periods T_2 , T_3 , T_4 and T_5 between the second and third pulses, between the third and fourth pulses, between the fourth and fifth pulses and between the fifth and sixth pulses of the pulse train P1 bear relationships such as $T_2 = T_1/2 = T_1/2^1$, $T_3 = T_1/4 = T_1/2^2$, $T_4 = T_1/8 = T_1/2^3$ and $T_5 = T_1/16 = T_1/2^4$, respectively.

The change-over switch 2 is designed to be controlled by the rectangular wave R1 from the output terminal 19 of the timing signal generator circuit 17 in such a manner that the movable contact c may lie on the fixed contacts a and b when the rectangular wave R1 has the values "1" and "0" respectively. Further, the reset switch 9 of the aforementioned integration circuit 3 is adapted to be closed by the reset pulse P4 derived from the output terminal 24 of the switching signal generator circuit 17. Moreover, the pulse train P1 and the pulse P2 are applied as trigger pulse trains to trigger pulse input terminals e of the aforesaid flip-flop circuits 13 and 14 from the output terminals 20 and 22 of the timing signal generator circuit 17, respectively. In this case, when the pulse of the pulse train P1 is applied to the terminal e of the flip-flop circuit 13 which the compared output Q fed to its terminal d from the comparator circuit 12 has the value "1," the flip-flop circuit 13 is set and when the pulse of the pulse train P1 is applied to the terminal e while the compared output Q fed to the terminal d has the value "0" the flip-flop circuit 13 is reset. The flip-flop circuit 13 derives from its "yes" output terminal y a rectangular wave output R3 which has a value "1" of binary indication while the circuit is set and has a value "0" while the circuit 13 is reset. The change-over switch 11 above mentioned is adapted to be controlled by the output R3 such that the movable contact c of the switch 11 may lie on its fixed contacts a and b when the output R3 has the values "1" and "0", respectively. When the pulse P2 is fed to the terminal e of the flip-flop circuit 14 while the compared output Q applied to its terminal d from the comparator circuit 12 has the value "1," the flip-flop circuit 14 is set and when the pulse P2 is ap-

plied to the terminal e while the compared output Q fed to the terminal d has the value "0," the flip-flop circuit 14 is reset. The flip-flop circuit 14 derives from its "not" output terminal n a rectangular wave output R4 which has a value "0" of binary indication while the circuit is set and has a value "1" while it is reset.

The rectangular wave R2 derived at the output terminal 21 of the timing signal generator circuit 17 is applied to one input line 36a of an "and" gate circuit 35 having two inputs, while the clock pulse train CP1 derived from the waveform shaping circuit 16 is applied to the other input line 36b of the "and" gate circuit 35. While the rectangular wave R2 has the value "1," one portion of the clock pulse train CP1 passes through the gate circuit 35 to provide a clock pulse train CP1' such as shown in FIG. 21, which is supplied to one input line 38b of an "and" gate circuit 37 having two inputs. While, the output R3 derived at the "yes" output terminal y of the aforesaid flip-flop circuit 13 is applied to the other input line 38a of the "and" gate circuit 37 through fixed and movable contacts a and c of a change-over switch 39.

One portion of the output R3 at the output terminal y of the flip-flop circuit 13 is fed to an inverter circuit 41 to derive therefrom an output R3' which is opposite in polarity to the output R3 (in the case of the output R3 being "1," the output R3' is "0" and, in the case of the former being "0," the latter "1"). The output R3' thus obtained is fed to the input line 38a of the "and" gate circuit 37 through the fixed and movable contacts b and c of the change-over switch 39. In this case, the change-over switch 39 is designed to be switchingly controlled so that its movable contact c may lie on the fixed contacts a and b while the output R4 derived from the "not" output terminal n of the flip-flop circuit 14 has the values "0" and "1," respectively.

In the period during which the output R3 and R3' fed to the input line 38a of the "and" gate circuit 37, has the value "1," the gate circuit 37 permits the passage therethrough of the clock pulse train CP1' fed thereto from the "and" gate circuit 35 to provide a clock pulse train CP1'', which is supplied to a pulse counter 42. In this case, the pulse counter 42 is constructed so that the content of counting is reset by the reset pulse P3 derived from the output terminal 23 of the timing signal generator circuit 17. The pulse counter 42 sequentially counts pulses of the pulse train CP1'' and the counted content is supplied to an indicator 43, thereby providing a digital indication of the content of counting achieved by the counter 42. The indicator 43 is supplied with the output R4 from the flip-flop circuit 14 and designed to provide a digital indication of the content of the counter 42 with "—" when the output R4 is "0" and a digital indication with "+" when the output R4 is "1."

The foregoing has outlined the construction of one example of this invention and the following will describe its operation on the assumption that the analog input voltage V_1 from the analog input signal source 1 is negative and that the operation starts from the time t_0 .

Since the rectangular wave R1 derived from the output terminal 19 of the timing signal generator circuit 17 is of the value "1" between t_0 and t_{32} as shown in FIG. 2C, the contact c of the change-over switch 2 lies on the side of the contact a in this period. Accordingly, the input voltage $-V_1$ is integrated by the integrator circuit

3 from the time t_0 and the output voltage E (hereinafter referred to as E_{32}) derived at the output terminal 8 of the integrator circuit 3 at the time t_{32} is given by the following equation.

$$+ E_{32} = + \frac{1}{RC} \int_{t_0}^{t_{32}} V_p dt \quad (1)$$

where R is the value of the resistor 6 and C that of the capacitor 7.

Thus, the rectangular wave R1 becomes "0" at the time t_{32} , so that the contact c of the change-over switch 2 is changed over to the side of the contact b at the time t_{32} . While, the output Q from the comparator circuit 12 at the time t_{32} has the value "1" because the input voltage to the comparator circuit 12 at that time is the output voltage E_{32} from the integrator circuit 3 and because the voltage E_{32} is positive, and the output Q is applied to the terminal d of the flip-flop circuit 13. At the time t_{32} the pulse of the pulse train P1 is derived at the output terminal 20 of the timing signal generator circuit 17 as depicted in FIG. 2D and is fed to the input terminal e of the flip-flop circuit 13. Consequently, the flip-flop circuit 13 is set at the time t_{32} and the output R3 derived from the output terminal y becomes "1" at the time t_{32} , so that the contact c of the change-over switch 11 is changed over to the side of the contact a.

Thus, the positive reference voltage $+V_p$ from the reference voltage source 10P is applied to the integrator 3 through the contacts a and c of the change-over switch 11 and those b and c of the change-over switch 2 from the time t_{32} and the reference voltage $+V_p$ is thereby integrated. The output voltage E (hereinafter referred to as E_{48}) derived at the output terminal 8 of the integration circuit 3 at the time t_{48} has a value given by the following equation.

$$E_{48} = + E_{32} - \frac{1}{RC} \int_{t_{32}}^{t_{48}} V_p dt \quad (2) \quad 40$$

In this case, the value of the voltage $+V_p$ is pre-selected such that the value $|E_K|$ expressed by the following equation

$$- E_K = - \frac{1}{RC} \int_{t_0}^{t_{32}} V_p dt \quad (3)$$

may be less than a predetermined maximum value of the output $|+E_{32}|$ given by the Equation (1).

The compared output Q, which is "1" or "0" at the time t_{48} dependent upon whether the value of the output E_{48} at the time t_{48} given by the Equation (2) is positive or zero or negative, is applied to the input terminal d of the flip-flop circuit 13. While, the pulse of the pulse train P1 derived at the output terminal 20 of the timing signal generator circuit 17 at the time t_{48} , shown in FIG. 2D, is applied to the input terminal e of the flip-flop circuit 13. Theefore, in the case where the compared Q is "1" at the time t_{48} , that is, where the value of the output E_{48} is positive or zero at that time, the flip-flop circuit 13 having been held in its set state is not altered to the reset state but in the case where the compared output Q is "0," that is, where the value of the output E_{48} is negative, the flip-flop circuit 13 held in the set state is altered to the reset state. Accordingly, in the event that the value of the output E_{48} is positive or zero

at the time t_{48} , the contact c of the changeover switch 11 held on the side of the contact a still remains as it is but, in the event of the output E_{48} being negative, the contact c of the switch 11 is changed over to the side of the contact b at the time t_{48} .

Where the value of the output E_{48} is positive at the time t_{48} , the reference $+V_p$ is continuously integrated by the integrator 3 from the time t_{48} and the output voltage E (hereinafter referred to as E_{56}) derived at the output terminal 8 of the integration circuit 3 at the time t_{56} has a value given by the following Equation (4a) and where the output E_{48} is zero the first term of the Equation (4a) is "0," so that the output E_{56} has a value given by the following Equation (4a').

$$E_{56} = + E_{48} - \frac{1}{RC} \int_{t_{48}}^{t_{56}} V_p dt \quad (4a)$$

$$- E_{56} = - \frac{1}{RC} \int_{t_{48}}^{t_{56}} V_p dt \quad (4a')$$

In the event that the value of the output E_{48} is negative at the time t_{48} , the negative voltage $-V_N$ from the reference voltage source 10N is supplied to the integration circuit 3 through the contacts b and c of the change-over switch 11 and those b and c of the change-over switch 2 and is integrated from the time t_{48} . The output E_{56} derived at the output terminal 8 of the integration circuit 3 at the time t_{56} has a value given by the given equation.

$$E_{56} = - E_{48} + \frac{1}{RC} \int_{t_{48}}^{t_{56}} V_N dt \quad (4b)$$

Similarly, if the value of the output E_{56} at the time t_{56} is positive or zero, the flip-flop circuit 13 is still held in its set state and, if negative, the flip-flop circuit 13 is altered to its reset state. After all, where the value of the output E_{56} is positive or zero at the time t_{56} , an output E_{60} derived at the output terminal 8 of the integration circuit 3 at the time t_{60} has a value given by the following Equation (5a) or (5a') and, if negative, the output E_{60} has a value given by the following Equation (5b).

$$E_{60} = + E_{56} - \frac{1}{RC} \int_{t_{56}}^{t_{60}} V_p dt \quad (5a)$$

$$- E_{60} = - \frac{1}{RC} \int_{t_{56}}^{t_{60}} V_p dt \quad (5a')$$

$$E_{60} = - E_{56} + \frac{1}{RC} \int_{t_{56}}^{t_{60}} V_N dt \quad (5b)$$

Likewise, in the case where the value of the output E_{60} is positive or zero at the time t_{60} , an output E_{62} derived at the output terminal 8 of the integration circuit 3 at the time t_{62} has a value given by the following Equation

(6a) or (6a') and, if negative, the output E_{60} has a value given by the following Equation (6b).

$$E_{62} = +E_{60} - \frac{1}{RC} \int_{t_{60}}^{t_{62}} V_P dt \quad (6a)$$

$$-E_{62} = -\frac{1}{RC} \int_{t_{60}}^{t_{62}} V_P dt \quad (6a') \quad 10$$

$$E_{62} = -E_{60} + \frac{1}{RC} \int_{t_{60}}^{t_{62}} V_N dt \quad (6b) \quad 15$$

In the event that the value of the output E_{62} is positive or zero at the time t_{62} , an output E_{63} derived at the output terminal 8 of the integration circuit 3 at the time t_{63} has a value given by the following Equation (7a) or (7a') and if negative, the output E_{62} has a value given by the following Equation (7b).

$$E_{63} = +E_{62} - \frac{1}{RC} \int_{t_{62}}^{t_{63}} V_P dt \quad (7a)$$

$$-E_{63} = -\frac{1}{RC} \int_{t_{62}}^{t_{63}} V_P dt \quad (7a') \quad 30$$

$$E_{63} = +E_{62} - \frac{1}{RC} \int_{t_{62}}^{t_{63}} V_N dt \quad (7b)$$

Thus, at the time t_{63} , the reset pulse P4 which has the value "1" from the time t_{63} to t_{64} is derived at the output terminal 24 of the timing signal generator circuit 17, so that the reset switch 9 is closed from the time t_{63} to t_{64} and the value of the output E derived at the output terminal 8 of the integration circuit 3 from a time a little past t_{63} to t_{64} . Consequently, the output E (hereinafter referred to as E_{64}) at the time t_{64} is "0."

The times t_{64} , t_{96} , t_{112} , t_{120} , t_{124} , t_{126} , t_{127} and t_{128} , t_{129} , t_{176} , t_{184} , t_{188} , t_{190} , t_{191} and t_{192} , . . . correspond to those t_0 , t_{32} , t_{48} , t_{56} , t_{60} , t_{62} , t_{63} and t_{64} respectively, at which the same operations as those above described are achieved.

By the way, the rectangular wave R2, which has the value "1" from the time t_{48} to t_{64} , from t_{112} to t_{128} , . . . as depicted in FIG. 2E, is applied to the input line 36a of the "and" gate circuit 35 to derive therefrom a pulse train CP1' such as shown in FIG. 21 from the time t_{48} to t_{64} , from t_{112} to t_{128} , . . . which is fed to the input line 38b of the "and" gate circuit 37. While, the rectangular wave R3 derived at the output terminal y of the flip-flop circuit 13 has the value "1" while the circuit 13 is in the set state and has the value "0" while the circuit 13 is in the reset state. Such a rectangular wave R3 is supplied to the input line 38a of the "and" gate circuit 37. Since the compared output Q has the value "1" at the time t_{32} as above described, the flip-flop circuit 14

is set by the pulse P2 at the time t_{32} , and accordingly the output R4 derived at its output terminal n always has the value "0" after the time t_{32} , thereby holding the movable contact c of the change-over switch 39 on the side of the contact a.

Accordingly, in the periods during which the rectangular wave R3 has the value "1" between the times t_{48} and t_{64} , between t_{112} and t_{128} , . . ., the pulse train CP1' is applied to the "and" gate circuit 37 to provide a pulse train CP1'', which is supplied to the counter 42. In this case, the counter 42 is set in advance at the times t_{47} , t_{111} , . . . prior to t_{48} , t_{112} , . . .

Consequently, the counter 42 counts the number of pulses of the pulse train CP1'' derived from the "and" gate circuit 37 between the times t_0 and t_{64} , between t_{64} and t_{128} , . . . and the number of the pulses counted is indicated in the digital form on the indicator 43 from the times t_{64} , t_{128} , . . . until the counter 42 is reset by the pulses P3 obtained at the times t_{111} , t_{175} , . . ., respectively. The number of the pulses counted by the counter 42 is obtained as a value proportional to the integrated output $|+E_{32}|$. Further, in this case, since the output R4 is fed to the indicator 43, the indicator 43 also provides the indication "—". This will become apparent from the following concrete example.

Namely, let it be assumed for the sake of brevity that the input voltage $-V_I$ is a constant voltage and that the integrated output $|+E_{32}|$ expressed by the Equation (3) is equal to a maximum value of the output $|+E_{32}|$ expressed by the Equation (1).

In such a case, from the Equations (1) and (3) the following relationship can be obtained:

$$\left| \frac{1}{RC} \int_{t_0}^{t_{32}} V_I dt \right| = \left| -\frac{1}{RC} \int_{t_0}^{t_{32}} V_P dt \right|$$

$$| -V_I | = | +V_P | \quad (8)$$

Therefore, the output E from the integration circuit 3 linearly increases in a positive direction with a gradient corresponding to the values of R and C from the time t_0 and reaches a point X_{10} at which the output $+E_{32}$ (hereinafter referred to as $+E_{32-1}$) based on the Equation (1) at the time t_{32} is produced, as indicated by a line U_{10} in FIG. 2J. Since the output $+E_{32-1}$ is positive in this case, the compared output Q has the value "1" as shown in FIG. 2K₁. Consequently, the flip-flop circuit 13 is set based on the pulse of the pulse train P1 at the time t_{32} and the rectangular wave R3 derived at the output terminal y of the flip-flop circuit 13 comes to have the value "1" from the time t_{32} as shown in FIG. 2L₁, so that the reference voltage $+V_P$ becomes integrated by the integration circuit 3 from the time t_{32} . If this integration proceeds to the time t_{64} , the time interval between the times t_0 and t_{32} and that $(T_1 + T_2 + T_3 + T_4 + T_5 + T_6)$ (T_6 being the time between t_{63} and t_{64} and bearing a relationship $T_6 = T_5$) between t_{32} and t_{64} are equal to each other. Accordingly, the integrated output E linearly decreases from the position of the point X_{10} at the time t_{32} with a gradient reverse to the line U_{10} and reaches a point X_{16} at the time t_{64} when the output E has the value "0." Therefore, as indicated by a line U_{11} in FIG. 2J, the integrated output E decreases along a straight line joining the point X_{10} with that X_{16} and reaches a point X_{11} at the time t_{48} at which the output E_{48} (hereinafter referred to as E_{48-1}) based on the Equation (2) is produced. In this case, the

output E_{48-1} is positive and the compared output Q has the value "1," so that the flip-flop circuit 13 is held in the set state. Accordingly, the change-over switch 11 is not changed over and the integrated output E continues to decrease similarly along a straight line joining the point $X1_0$ with that $X1_6$ from the time t_{48} as indicated by a line $U1_2$ and reaches a point $X1_2$ at the time t_{56} at which the output (hereinafter referred to as E_{56-1} based on the the Equation (4a) is produced. Also in this case, the output E_{56-1} is positive, so that the integrated output E similarly continues to decrease from the position of the point $X1_2$ at the time t_{56} down to a point $X1_3$ at the time t_{60} at which the output E_{60} (hereinafter referred to as E_{60-1}) based on the Equation (5a) is produced, as indicated by a line $U1_3$. Thereafter, the integrated output E likewise decreases from the time t_{60} down to a point $X1_4$ at the time t_{62} at which the output E_{62} (hereinafter referred to as E_{62-1}) based on the Equation (6a) is obtained, as indicated by a line $U1_4$. Then, the integrated output E still continues to decrease down to a point $X1_5$ at the time t_{63} at which the output E_{63} (hereinafter referred to as E_{63-1}) based on the Equation (7a) is obtained, as indicated by a line $U1_5$. Thereafter, the reset switch 9 of the integration circuit 3 is closed between the time t_{63} and t_{64} , so that the output E from the integration circuit 3 has the value "0" until the time t_{64} a little past t_{63} as shown by a line $U1_6$. In this case, the output R3 from the flip-flop circuit 13 has the value "1" for the entire period during which the rectangular wave R2 derived at the output terminal 21 of the timing signal generator circuit 17 has the value "1," as illustrated in FIG. 2L₁. While, the flip-flop circuit 14 is set by the pulse P2 at the time t_{32} , so that the output R4 derived from its output terminal n comes to have the value "0" from the time t_{32} as illustrated in FIG. 2N₁.

Accordingly, the pulse CP1 derived from the clock pulse train CP' passes through the "and" gate circuit 37 for the entire period during which the rectangular wave R2 has the value "1," that is, for the period between the time t_{48} and t_{64} which is half as long as that between the times t_{32} and t_{64} , as shown in FIG. 2M₁ and the pulse CP1" is applied to the counter 42. Thus, the counter 42 counts 16 pulses in the period from the time t_0 to t_{64} and, based on the content counted, the indicator 43 indicates that the input voltage V_I is, for example, "-16V" until the counter 42 is subsequently reset. Thereafter, the counter 42 similarly counts 16 pulses in the periods between the times t_{64} and t_{128} , between t_{128} and t_{192} , . . . and the indicator 43 indicates that the input voltage V_I is "-16V." The indication "-16V" by the indicator 43 implies that the input voltage V_I is negative "16V" and is a maximum value of the input voltage V_I .

Assuming that the input voltage $|V_I|$ is half as low as that in the foregoing example, that is, the following relationship exists:

$$\left| \frac{1}{RC} \int_{t_0}^{t_{32}} V_I dt \right| = \left| -\frac{1}{2} \cdot \frac{1}{RC} \int_{t_0}^{t_{32}} V_P dt \right| \quad 60$$

$$| -V_I | = \left| \frac{1}{2} \cdot V_P \right| \quad (9)$$

the output E from the integration circuit 3 linearly increases with a gradient half as small as that of the aforementioned line $U1_0$ and reaches a point $X2_0$ at the time t_{32} at which the output $+E_{32}$ (hereinafter referred to as

$+E_{32-2}$) based on the Equation (1) is obtained, as indicated by a line $U2_0$ in FIG. 2J. In this case, the output $+E_{32-2}$ is positive, so that the compared output Q has the value "1" as shown in FIG. 2K₂. Consequently, the flip-flop circuit 13 is set based on the pulse of the pulse train P1 at the time t_{32} and the rectangular wave R3 derived at the output terminal y of the flip-flop circuit 13 comes to have the value "1" from the time t_{32} as shown in FIG. 2L₂, so that the reference voltage $+V_P$ becomes integrated by the integration circuit 3 from the time t_{32} . If this integration continues until the time t_{64} , the reference voltage $+V_P$ is the same as that in the case of the aforementioned line joining the points $X1_0$ and $X1_6$, with the result that the integrated output E decreases from the position of the point $X2_0$ at the time t_{32} with the same gradient as that of the line $U1_1$ and reaches a point $X2_6$ at the time t_{64} at which the output E is negative and equal to the output $|+E_{32-2}|$. Accordingly, the integrated output E decreases from the time t_{32} along a straight line joining the points $X2_0$ and $X2_6$ and reaches a point $X2_1$ at the time t_{48} at which the output E_{48} (hereinafter referred to as E_{48-2}) based on the Equation (2) is produced, as indicated by a line $U2_1$. The point $X2_1$, herein mentioned is a point at which the output E has the value "0" because the time between t_{32} and t_{48} and that between t_{48} and t_{64} are equal to each other. Therefore, the output Q has the value "1" at the time t_{48} , so that the flip-flop circuit 13 remains in the set state and accordingly the change-over switch 11 is not changed over. The integrated output E continues to decrease from the time t_{48} down to a point $X2_2$ at the time t_{56} at which the output E_{56} (hereinafter referred to as E_{56-2}) based on the Equation (4a') is obtained, as indicated by a line $U2_2$. Since the output E_{56-2} is negative in this case, the flip-flop circuit 13 is reset by the pulse of the pulse train P1 at the time t_{56} to provide the output R3 having the value "0." Accordingly, the contact c of the change-over switch 11 is changed over to the side of the contact b, causing the integration circuit 3 to integrate the negative reference voltage $-V_N$ from the time t_{56} . As a result of this, the integrated output E increases in a positive direction from the point $X2_2$ of the time t_{56} as indicated by a line $U2_3$. Since $|+V_P| = |-V_N|$ in this case, the line $U2_3$ extends from the position of the point $X2_2$ with a gradient reverse to that of the aforesaid line $U1_3$ toward the point $X2_6$ (the same point as that $X1_6$) at which the integrated output E has the value "0" at the time t_{64} and reaches a point $X2_3$ at the time t_{60} at which the output E_{60} (hereinafter referred to as E_{60-2}) based on the Equation (5b) is obtained. In this case, the output E_{60-2} is negative and the compared output Q has the value "0," so that the flip-flop circuit 13 remains in the reset state, and consequently the change-over switch 11 is not changed over. Accordingly, the integrated output E continues to increase in the positive direction from the position of the point $X2_3$ at the time t_{60} and reaches a point $X2_4$ at the time t_{62} at which the output E_{62} (hereinafter referred to as E_{62-2}) based on the Equation (6b) is obtained. Also in this case, the output E_{62-2} is positive, so that the integrated output E similarly continues to increase in the positive direction from the position of the point $X2_4$ at the time t_{62} as shown by a line $U2_5$ and reaches a point $X2_5$ at the time t_{63} at which the output E_{63} (hereinafter referred to as E_{63-2}) based on the Equation (7b) is obtained. Thereafter, the reset switch 9 is closed between the times t_{63} and t_{64} , with the result that the output E from the integration circuit 3 is zero from a time a little

past t_{63} to the time t_{64} as shown by a line $U2_6$. In this case, the output $R3$ from the flip-flop circuit 13 has the value "0" after the time t_{56} as illustrated in FIG. 2L₂. While, the output $R4$ from the flip-flop circuit 14 has the value "0" after the time t_{32} in the same manner as that previously described, as depicted in FIG. 2N₂. Consequently, the pulse train $CP1''$ is derived from the "and" gate circuit 37 only between the times t_{48} and t_{56} as shown in FIG. 2M₂ and is applied to the counter 42 . In this case, the time between t_{48} and t_{56} is half as long as that between t_{48} and t_{64} , so that the counter 42 counts eight pulses and the indicator 43 indicates it. In this case, the indicator provides an indication that the input voltage V_I is "-8V" because "-16V" is indicated in the case where the counter 42 counts 16 pulses as previously described. Thereafter, the counter 42 similarly counts eight pulses in the periods between t_{64} and t_{128} , between t_{128} and t_{192} , . . . respectively and the indicator 43 thus indicates that the input voltage V_I is "-8V." The present example has been described on the assumption that the value of the input voltage V_I is half as much as that in the above case in which "-16V" is indicated, that is, the relationship expressed by the Equation (9) is adopted. Accordingly, the indication of "-8V" implies that the input voltage V_I is accurately indicated.

Further, if the input voltage V_I is zero, the output E from the integration circuit 3 is zero between the times t_0 and t_{32} as indicated by $U3_0$ in FIG. 2J. However, the compared output Q has the value "1" at the time t_{32} as depicted in FIG. 2K₃, so that the output $R3$ from the flip-flop circuit 13 comes to have the value "1" from the time t_{32} . As a result of this, the reference voltage $+V_P$ is integrated by the integration circuit 3 from the time t_{32} , and accordingly if this integration is carried out until the time t_{64} , the integrated output E decreases with the same gradient as that of the line $U2_1$ from the position of the point $X3_0$ of the output E being zero at the time t_{32} as in the above case and reaches a point $X3_6'$ at the time t_{64} at which the output E has a value equal to the negative output $|+E_{32-1}|$. Accordingly, the integrated output E decreases from the time t_{32} along a line joining the points $X3_0$ and $X3_6'$ (increases in the negative direction) as indicated by a line $U3_1$ and reaches a point $X3_1$ at the time t_{48} at which the output E_{48} (hereinafter referred to as E_{48-3}) based on the Equation (2) (the first term being zero) is obtained. In this case, the value of the output E_{48} is negative and equal to that of the aforesaid output $|+E_{32-1}|$, so that the compared output Q has the value "0" at the time t_{48} and the flip-flop circuit 13 is reset at the time t_{48} and the output $R3$ therefrom has the value "0." Therefore, the change-over switch 11 is changed over to cause the integration circuit 3 to integrate the reference voltage $-V_N$. As a result of this, the integrated output E increases from the point $X3_1$ in the positive direction to reach a position $X3_2$ (the same position as the point $X2_2$) at the time t_{56} at which the output E_{56} (hereinafter referred to as E_{56-3}) based on the Equation (4b) is obtained, as indicated by a line $U3_2$. In this case, the output E_{56-3} is negative, so that the output $R3$ from the flip-flop circuit 13 still has the value "0." Accordingly, the integrated output E increases from the point $X3_2$ along a line $U3_3$ (the same as the line $U2_3$) to reach a point $X3_3$ (the same as that $X2_3$), then still increases from the point $X3_3$ along a line $U3_4$ (the same as that $U2_4$) to a point $X3_4$ (the same as that $X2_4$) and further increases from the point $X3_4$ along a line $U3_5$ (the same as that

$U2_5$) to a point $X3_5$ (the same as that $X2_5$). Thereafter, the reset switch 9 is closed between the times t_{63} and t_{64} , so that the output E from the integration circuit 3 is zero from a time a little past t_{63} to the time t_{64} as indicated by a line $U3_6$. In this case, the output $R3$ from the flip-flop circuit 13 has the value "1" only between the times t_{32} and t_{48} as shown in FIG. 2K₃. While, even if the output $R4$ from the flip-flop circuit 14 has the value "0" after the time t_{32} in the same manner as previously described as illustrated in FIG. 2N₃, the clock pulse train $CP1'$ is applied to the "and" gate circuit 37 only between the times t_{48} and t_{64} , so that the clock pulse $CP1''$ is not derived from the "and" gate circuit 37 as depicted in FIG. 2M₃. Consequently, the counter 42 does not count any pulse between the times t_0 and t_{64} and the indicator 43 provides an indication that the input voltage V_I is "0." Thereafter, the counter 42 similarly does not count any pulse between the times t_{64} and t_{128} , between t_{128} and t_{192} , . . . , so that the indicator 43 provides an indication that the input voltage V_I is "OV." Since the input voltage V_I is zero in the present example, this implies that an accurate indication of the input voltage V_I can be obtained.

A description will be given, though not in detail, in connection with the case where the input voltage V_I is a constant negative voltage and is five-eighths times that in the case where the digital value of "-16V" is indicated by the indicator 43 , that is, the following relationship is adopted.

$$| -V_I | = | \frac{5}{8} V_P | \quad (10)$$

35 The integrated output E from the integrator circuit 3 increases in the positive direction from the time t_0 to reach a point $X4_0$ at the time t_{32} at which the output E has a value five-eighths times that of the aforesaid output E_{32-1} , that is, a value $\frac{5}{8} E_{32-1}$ (hereinafter referred to as E_{32-4}), as shown by a line $U4_0$. From the point $X4_0$ the integrated output E decreases down to a point $X4_1$ at the time t_{48} at which a value E_{48-4} of a positive output $| E_{48-4} - (E_{32-1} - E_{32-4}) |$ based upon the Equation (2) is obtained, as indicated by a line $U4_1$. The integrated output E further decreases from the point $X4_1$ and becomes negative and reaches a point $X4_2$ at the time t_{56} at which a value $-E_{56-4}$ of a negative output $| E_{56-4} - (E_{32-1} - E_{32-4}) |$ based on the Equation (4a) is obtained, as indicated by a line $U4_2$, and, further, the integrated output E increases from the point $X4_2$ in the positive direction to reach a point $X4_3$ at the time t_{60} at which the output E has the value "0" based on the Equation (5b), as shown by a line $U4_3$, and from thence the output E increases in the negative direction to a point $X4_4$ at the time t_{62} at which it has a value $-E_{62-4}$ equal to a negative output $| +E_{62-1} |$ based on the Equation (6a'), as indicated by a line $U4_4$, and from thence the output E further increases in the positive direction to a point $X4_5$ at the time t_{63} at which it has a value $-E_{63-4}$ equal to a negative output $| +E_{63-1} |$, as indicated by a line $U4_5$, and, the integrated output E has the value "0" from a time a little past t_{63} to the time t_{64} . In this case, the compared output Q , the output $R3$ from the flip-flop circuit 13 , the pulse train $CP1''$ from the "and" gate circuit 37 and the output $R4$ from the flip-flop circuit 14 are obtained as illustrated in FIGS. 2K₄, 2L₄, 2M₄ and 2N₄, respectively. Accordingly, the counter 42 counts 10

pulses in all between the times t_0 and t_{64} and the indicator 43 indicates that the input voltage V_I is “-10V.” Also between the times t_{64} and t_{128} , between t_{128} and t_{192} , . . . the indicator 43 similarly provides the indication of “-10V.” This implies that an accurate indication of the input voltage V_I is obtained, because $-16 \times \frac{5}{8} = -10$ based on the relationship of the Equation (10). Also in the event that the input voltage V_I is negative and has a value other than that in the foregoing, a digital indication is similarly provided corresponding to the value of the input voltage V_I . After all, in the above example, an analog-to-digital conversion characteristic expressed by the following function.

$$|V_I| = N \quad 15 \quad (11)$$

is obtained as shown in FIG. 3 in which the ordinate represents the value of the input voltage $|V_I|$ and the abscissa the value of the counting number N of the counter 42.

A brief description will be made in connection with the case where the input voltage V_I has a certain positive value and the operation similarly starts from the time t_0 .

In the same manner as that previously described the input voltage $+V_I$ is integrated by the integration circuit 3 from the time t_0 and at the time t_{32} the integrated output E is obtained with a value $-E_{32}$ given by the following equation corresponding to the aforesaid Equation (1).

$$-E_{32} = -\frac{1}{RC} \int_{t_0}^{t_{32}} V_I dt \quad 12$$

Further, the contact c of the change-over switch 2 is changed over to the side of the contact b from the time t_{32} . While, the compared output Q has the value “0” at the time t_{32} because the output $-E_{32}$ is negative, so that the output $R3$ from the flip-flop circuit 13 does not become “1” but remains “0” at the time t_{32} and the change-over switch 11 is not changed over. As a result of this, the integration circuit 3 comes to integrate the negative reference voltage $-V_N$ from the reference voltage source 10N from the time t_{32} to produce the integrated output E having a value E_{48} given by the following equation at the time t_{48} .

$$E_{48} = -E_{32} + \frac{1}{RC} \int_{t_{32}}^{t_{48}} V_N dt \quad 13$$

In this case, the value of the voltage $-V_N$ is selected such that the value of an integrated output $|E_{48}'|$ expressed by the following equation:

$$+E_{48}' = +\frac{1}{RC} \int_{t_0}^{t_{32}} V_N dt \quad 14$$

as is the case with the Equation (3) may be less than a predetermined maximum value of the output $|-E_{32}|$ given by the Equation (12') and such that $|-E_{48}'| = |+E_{48}'|$ because the voltage $-V_N$ bears a relationship $|+V_P| = |-V_N|$.

If the output E_{48} at the time t_{48} given by the Equation (13) is positive or zero, the compared output Q has a value “1” at the time t_{48} and if negative, it has the value “0.” Thereafter, in the manner above described in the

case where the input voltage V_I is negative, if the output E_{48} at the time t_{48} given by the Equation (13) is positive or zero, the integrated output E is obtained as an output E_{56} given by the following Equation (15a) or (15a') and if negative, it is obtained as an output E_{56} given by the following Equation (15b).

$$E_{56} = +E_{48} - \frac{1}{RC} \int_{t_{48}}^{t_{56}} V_P dt \quad 15a$$

$$-E_{56} = -\frac{1}{RC} \int_{t_{48}}^{t_{56}} V_P dt \quad 15a'$$

$$E_{56} = -E_{48} + \frac{1}{RC} \int_{t_{48}}^{t_{56}} V_N dt \quad 15b$$

Similarly, if the output E_{56} at the time t_{56} expressed by the Equation (15a) or (15b) is positive or zero, the integrated output E at the time t_{60} is obtained as an output E_{60} given by the following equation (16a) or (16a') and if the former is negative or the output $-E_{56}$ expressed by the Equation (15a'), the latter is obtained as an output E_{60} given by the following Equation (16b).

$$E_{60} = +E_{56} - \frac{1}{RC} \int_{t_{56}}^{t_{60}} V_P dt \quad 16a$$

$$-E_{60} = -\frac{1}{RC} \int_{t_{56}}^{t_{60}} V_P dt \quad 16a'$$

$$E_{60} = -E_{56} + \frac{1}{RC} \int_{t_{56}}^{t_{60}} V_N dt \quad 16b$$

Further, the integrated output E at the time t_{62} is similarly obtained as an output E_{62} given by the following Equation (17a) or (17a') when the output E_{60} at the time t_{60} expressed by the Equation (16a) or (16b) is positive or zero and given by the following Equation (17b) when the output E_{60} is negative or the output $-E_{56}$ expressed by the Equation (16a'). Likewise, the integrated output E at the time t_{63} is obtained as an output E_{63} given by the following Equation (18a) or (18a') when the output E_{62} at the time t_{62} is positive or zero and given by the following Equation (18b) when the output E_{62} is negative, and, further, the integrated output E is made zero from a time a little past the time t_{63} to the time t_{64} .

$$E_{62} = E_{60} - \frac{1}{RC} \int_{t_{60}}^{t_{62}} V_P dt \quad 17a$$

$$-E_{62} = -\frac{1}{RC} \int_{t_{60}}^{t_{62}} V_P dt \quad 17a'$$

$$E_{62} = -E_{60} + \frac{1}{RC} \int_{t_{60}}^{t_{62}} V_{Ndt} \quad (17b)$$

$$E_{63} = E_{62} - \frac{1}{RC} \int_{t_{62}}^{t_{63}} V_{Pdt} \quad (18a)$$

$$-E_{63} = -\frac{1}{RC} \int_{t_{62}}^{t_{63}} V_{Pdt} \quad (18a')$$

$$E_{63} = -E_{62} + \frac{1}{RC} \int_{t_{62}}^{t_{63}} V_{Ndt} \quad (18b)$$

Then, the times $t_{64}, t_{96}, t_{112}, t_{120}, t_{124}, t_{126}, t_{127}$ and $t_{128}; t_{128}, t_{160}, t_{176}, t_{188}, t_{190}, t_{191}$ and $t_{192}; \dots$ correspond to those $t_0, t_{32}, t_{48}, t_{56}, t_{60}, t_{62}, t_{63}$ and t_{64} respectively as previously described and the same operations as above described are achieved.

Also in this example, the pulse trains $CP1'$ and $CP1''$ are derived from the "and" gate circuits 35 and 37, respectively in the same manner as in the case of the input voltage V_I being negative and the pulses of the pulse train $CP1''$ are counted by the counter 42 and the number of the pulses thereby counted is indicated by the indicator 43 until resetting of the counter 42 in the same manner as in the case of the input voltage V_I being negative. The number of pulses counted by the counter 42 is obtained as a value proportional to the integrated output $|-E_{32}|$ given by the Equation (12). Although not described in detail, this will becomes more apparent from the following concrete example.

For the sake of brevity, let it be assumed that the input voltage V_I is a certain positive voltage and that the output $|+E_k|$ expressed by the Equation (14) is equal to a maximum value of the output $|E_{32}|$ by the Equation (12). The integrated output E increases in the negative direction from the time t_0 reaches a point $X5_0$ at the time t_{32} at which it has a negative value $-E_{32-5}$ equal to $|E_{32-1}|$ based on the Equation (12), as shown by a line $U5_0$, from thence the output E increases in the positive direction to reach a point $X5_1$ at the time t_{48} at which it has a value $-E_{48-5}$ half times smaller than that of the output $-E_{32-5}$ based on the Equation (13), as indicated by a line $U5_1$, from thence the output E increases in the positive direction to reach a point $X5_2$ at the time t_{56} at which it has a value $-E_{56-5}$ half times smaller than that of the output $|+E_{48-5}|$ based on the Equation (15b), as indicated by a line $U5_2$, from thence the output E increases in the positive direction to reach a point $X5_3$ at the time t_{60} at which it has a value $-E_{60-5}$ half times smaller than that of the output $|+E_{56-5}|$ based on the Equation (16b), as indicated by a line $U5_3$, from thence the output E increases in the positive direction to reach a point $X5_4$ at the time t_{62} at which it has a value $-E_{62-5}$ half times smaller than that of the output $|+E_{60-5}|$ based on the Equation (17b), as indicated by a line $U5_4$, and from thence the output E further increases in the positive direction to reach a point $X5_5$ at the time t_{63} at which it has a value $-E_{63-5}$ half times smaller than that of the output $-E_{62-5}$ based on the Equation (18b), as indicated by a line $U5_5$, and the output E has the value "0" from a time a little past the time t_{63} to the time t_{64} . In this case, the compared output Q , the output $R3$ from the flip-flop circuit 13, the

output $R3'$ from the inverter circuit 41 and the pulse train $CP1''$ from the "and" gate circuit 37 are obtained as illustrated in FIGS. 2K₅, 2L₅, 2O₅ and 2M₅, respectively.

Consequently, the counter 42 counts sixteen pulses in all between the times t_0 and t_{64} and the indicator 43 indicates "16V." Since the output $R4$ for this indication is always "1," a sign "+" is added to the indication "16V" and "+16V" is indicated by the indicator 43. Also between the times t_{64} and t_{128} , between t_{128} and t_{192} the indication "+16V" is similarly provided by the indicator 43. In the example, the input voltage V_I has a value equal to the absolute value $|V_I|$ of the voltage V_I in the case of "-16V" being indicated by the indicator 43 but is positive in polarity. Accordingly, the indication "+16V" implies that the voltage V_I is accurately indicated.

Assuming that the input voltage V_I is a certain positive voltage and that the output voltage $|-E_{32}|$ expressed by the Equation (12) is five-eighths times that in the above example, the integrated output E increases in the negative direction from the time t_0 and reaches a point $X6_0$ at the time t_{32} at which it has a value $-E_{32-6}$ five-eighths times smaller than the aforesaid negative output $-E_{32-5}$ based on the Equation (12), as indicated by a line $U6_0$, from thence the output E increases in the positive direction to reach a point $X6_1$ at the time t_{48} at which it has a value $-E_{48-6}$ of the output $-\{|E_{48-5}| - (|E_{32-5}| - |E_{32-4}|)\}$ based on the Equation (13), as indicated by a line $U6_1$, from thence the output E increases in the positive direction to become positive and reach a point $X4_2$ at the time t_{56} at which it has a value $+E_{56-4}$ of the positive output $\{|-E_{56-5}| - (|-E_{32-5}| - |-E_{32-4}|)\}$ based on the Equation (15b), as indicated by a line $U6_2$, from thence the output E increases in the negative direction to reach a point $X6_3$ at the time t_{60} at which it has the value "0" based on the Equation (16a), as indicated by a line $U6_3$, from thence the output E increases in the negative direction to reach a point $X4_4$ at the time t_{62} at which it has a value $-E_{62-6}$ equal to that of the negative output $|-E_{62-1}|$ based on the Equation (17a'), as indicated by a line $U6_4$, and from thence the output E increases in the positive direction to reach a point $X6_5$ at the time t_{65} at which it has a value $-E_{63-6}$ equal to that of the negative output $|-E_{63-1}|$ based on the Equation (18b), as indicated by a line $U6_5$, and the output E is made zero from a time a little past t_{63} to the time t_{64} . In this case, the compared output Q , the outputs $R3$ and $R4$ from the flip-flop circuits 13 and 14, the output $R3'$ and the pulse train $CP1''$ are obtained as illustrated in FIGS. 2K₆, 2L₆ and 2N₆, 2O₆ and 2M₆, respectively.

Accordingly, the pulse counter 42 counts ten pulses in all between the times t_0 and t_{64} and the indicator 43 indicates that the input voltage V_I is "10V." Further, the indicator 43 indicates that it is "+" and accordingly it provides an indication "+10V." Also between the times t_{64} and t_{128} , between t_{128} and t_{192} , . . . the indication "+10V" is similarly provided by the indicator 43. In the present example, the voltage $|-E_{32}|$ is five-eighths times that in the case where the indication "16V" is obtained, so that $+16 \times \frac{5}{8} = +10$ and the indication "+10V" implies that the input voltage V_I is accurately indicated. Also in the case where the input voltage V_I is positive and has a value other than that in the foregoing, a digital indication can be likewise obtained corresponding to the value of the input voltage

V_I and, after all, an analog-to-digital conversion characteristic I shown in FIG. 3 is obtained.

The foregoing has been described to obtain the analog-to-digital characteristic expressed by the Equation (11) or shown in FIG. 3. It will be seen from the foregoing that if the values of the reference voltages $|+V_P|$ and $|V_N|$ are increased by α times or the time T_C for integration of the input voltage V_I is increased by α times (α being a desired positive number), an analog-to-digital conversion characteristic expressed by the Equation (19) can be obtained.

$$|V_I| = \alpha \cdot N \quad (19)$$

Referring now to FIG. 4, another example of this invention will hereinbelow be described in detail.

In the present example elements corresponding to those in FIG. 1 are identified by the same reference numerals and characters and no detailed description will be repeated therefor. The present example has the following construction in addition to that of FIG. 1.

Namely, for example, four coincidence detecting circuits 51a to 51d are provided, which are adapted to be supplied with a counted output G from a counter 52 and setting outputs F_a to F_d representative of digital values from setting circuits 53a to 53d, respectively. In this case, the counter 52 is constructed to count a clock pulse train CP1" produced by supplying the clock pulse train CP1 from the waveform shaping circuit 16 to an "and" gate circuit 54. While, the aforesaid timing signal generator circuit 17 has another terminal 55 in addition to the aforementioned ones, from which is derived a rectangular wave R5 such as depicted in FIG. 2P which has the value "1" between the times t_{32} and t_{65} , between t_{96} and t_{129} , . . . and has the value "0" in the other periods, and the "and" gate circuit 54 is adapted to be open in the periods during which the rectangular wave R5 has the value "1." Accordingly, the pulse train CP1" is obtained between the times t_{32} and t_{65} , between t_{96} and t_{129} , . . . as shown in FIG. 2Q. Further, the setting circuits 53a to 53d are designed so that their setting outputs F_a to F_d can be set from the outside in the form of different digital values but in the order of F_a , F_b , F_c and F_d .

When the value of the counted output G coincides with the setting outputs F_a , F_b , F_c and F_d , respectively, coincidence outputs H_a , H_b , H_c and H_d are sequentially derived from the coincidence detecting circuits 51a, 51b, 51c and 51d, respectively and the coincidence output H_a is applied to a reset terminal r of a flip-flop circuit 56a and a set terminal s of a flip-flop circuit 56b, the output H_b a reset terminal r of the flip-flop circuit 56b and a set terminal s of a flip-flop circuit 56c, the output H_c a reset terminal r of the flip-flop circuit 56c and a set terminal s of a flip-flop circuit 56d and the output H_d a reset terminal r of the flip-flop circuit 56d. To a set terminal s of the flip-flop circuit 56a is applied the pulse P2 from the output terminal 22 of the timing signal generator circuit 17. Further, each of outputs K_a to K_d from "yes" output terminals y of the flip-flop circuits 56a to 56b is supplied to the one input line of each of "and" gate circuits 57a to 57d having two inputs. While, a zero level detecting circuit 58 is provided which is adapted to be supplied with the pulse P2 from the output terminal 22 of the timing signal generator circuit 17 and the compared output Q from the com-

parator circuit 12 and to obtain a detected output L each time supplied with the pulse P2, which output L has the value "1" from the time of obtaining the pulse P2 until the compared output Q is altered from "1" to "0" or "0" to "1" and has the value "0" in the other periods. The output L from the zero level detecting circuit 58 is supplied to the other input lines of the aforesaid "and" gate circuits 57a to 57d.

Further, four voltage sources 59a to 59d are provided corresponding to "and" gate circuits 57a to 57d and voltages V_a to V_d are applied from these voltage sources 59a to 59d to the input side of the amplifier 5 of the integration circuit 3 through switches 60a to 60d respectively and a common resistor 61. In this case, the switches 60a to 60d are adapted to be closed in the periods during which outputs M_a to M_d from the "and" gate circuits 57a to 57d have the value "1", respectively.

The foregoing has outlined the construction of the example shown in FIG. 4, which will be further described together with its operation in connection with the case where the input voltage V_I is negative.

Each time the pulse P2 is obtained, the output L from the zero level detecting circuit 58 has the value "1" from the times t_{32} , t_{96} , . . . when the pulse P2 is obtained to the time when the compared output Q is altered from "1" to "0" or "0" to "1." Accordingly, between the times t_0 and t_{32} , between t_{64} and t_{96} , . . . the outputs M_a to M_d from the "and" gate circuits 57a to 57d have the value "0," so that the operations between the times t_0 and t_{32} , between t_{64} and t_{96} , . . . are exactly the same as those in the example of FIG. 1. However, since the output L from the zero level detecting circuit 58 has the value "1" between the times t_{32} and t_{64} , between t_{96} and t_{128} , . . ., the following operation is obtained in addition to the operations previously described in connection with FIG. 1.

Assume that digital numbers such as, for example, "6," "10," "14" and "17" are set in the setting circuits 53a, 53b, 53c and 53d, respectively. Further, let it be assumed that a resistor 61 has a value R equal to that of the resistor 6, that the voltages V_a , V_b and V_c derived from the voltage sources 59a, 59b and 59c are negative, that the voltage V_d derived from the voltage source 59d is positive and that the values of the voltages V_a to V_d relative to the voltage V_P are preselected so that the following relationship may be obtained in relation to the voltage E_K given by the aforesaid Equation (3).

$$-\frac{E_K}{4} = -\frac{1}{RC} \int_{t_0}^{t_{32}} (V_P - V_a) dt \quad (20a)$$

$$-\frac{E_K}{2} = -\frac{1}{RC} \int_{t_0}^{t_{32}} (V_P - V_b) dt \quad (20b)$$

$$-\frac{3}{4} \cdot E_K = -\frac{1}{RC} \int_{t_0}^{t_{32}} (V_P - V_c) dt \quad (20c)$$

$$+\frac{39}{12} E_K = \frac{1}{RC} \int_{t_0}^{t_{32}} (V_P + V_d) dt \quad (20d)$$

In such a case, the counter 52 counts pulses of the pulse train CP1''' from the time t_{32} and at the time t_{42} when the counter 52 has counted six pulses of the pulse train CP1''' the pulse output H_a is derived from the coincidence detecting circuit 51a as depicted in FIG. 2R_a. Similarly, at the times t_{50} , t_{58} and t_{64} when the counter 52 has counted 10, 14 and 17 pulses of the pulse train CP1'' from the time t_{32} respectively, the outputs H_b , H_c and H_d are derived from the coincidence detecting circuits 51b, 51c and 51d as shown in FIGS. 2R_b, 2R_c and 2R_d, respectively. Accordingly, the outputs K_a , K_b , K_c and K_d derived at the "tes" output terminals y of the flip-flop circuits 56a, 56b, 56c and 56d are obtained in the form of the outputs "1" between the times t_{32} and t_{42} , between t_{42} and t_{50} , between t_{50} and t_{58} and between t_{58} and t_{64} , as illustrated in FIGS. 2S_a, 2S_b, 2S_c and 2S_d, respectively.

Further, since the compared output Q is "1" at the time t_{32} as is the case with the foregoing example and is applied to the zero level detecting circuit 58, the output L therefrom is "1" from the time t_{32} by the cooperation with the pulse P2 shown in FIG. 2F. Therefore, the output M_a from the "and" gate circuit 57a is "1" from the time t_{32} , so that the switch 60a is closed from this time and the voltage V_a is applied to the integration circuit 3. 25

Consequently, if the output L, that is, the compared output Q continues to have the value "1" from the time t_{32} to t_{42} , only the output M_a has the value "1" between the times t_{32} and t_{42} based on the output K_a depicted in FIG. 2S_a, so that the voltages $+V_p$ and $-V_a$ are integrated by the integration circuit 3 between the times t_{32} and t_{42} . Since the integrated output E derived at the output terminal 8 of the integration circuit 3 at the time t_{32} is given by the following Equation (21) similar to the aforementioned (1), the integrated output E (hereinafter referred to as E_{32}) obtained at the time t_{42} has a value given by the following Equation (22).

$$+E_{32} = +\frac{1}{RC} \int_{t_0}^{t_{32}} V_p dt \quad (21)$$

$$+E_{42} = +E_{32} - \frac{1}{RC} \int_{t_{32}}^{t_{42}} (V_p - V_a) dt \quad (22) \quad 45$$

If the output L from the zero level detecting circuit 58 has the value "1" between the times t_{42} and t_{50} , only the output M_b has the value "1" between the times t_{42} and t_{50} based on the output K_b depicted in FIG. 2S_b to close only the switch 60b between the times t_{42} and t_{50} , during which the voltages $+V_p$ and $-V_b$ are integrated by the integration circuit 3 and the integrated output E (hereinafter referred to as E_{50}) therefrom at the time t_{50} has a value given by the following equation.

$$+E_{50} = +E_{42} - \frac{1}{RC} \int_{t_{42}}^{t_{50}} (V_p - V_b) dt \quad (23) \quad 60$$

Further, if the output L has the value "1" between the times t_{50} and t_{58} , only the output M_c has the value "0" between the times t_{50} and t_{58} based on the output K_c shown in FIG. 2S_c, so that the switch 60c is closed between the times t_{50} and t_{58} , during which the voltages $+V_p$ and $-V_c$ are integrated by the integration circuit

3 and the integrated output E (hereinafter be referred to as E_{58}) derived therefrom at the time t_{58} has a value given by the following equation.

$$+E_{58} = +E_{50} - \frac{1}{RC} \int_{t_{50}}^{t_{58}} (V_p - V_c) dt \quad (24)$$

10 Then, if the output L has the value "1" between the times t_{58} and t_{59} , only the output M_d has the value "1" between the times t_{58} and t_{59} based on the output K_d depicted in FIG. 2S_d, so that the switch 60d is closed between the times t_{58} and t_{59} . In this case, if the integration circuit 3 is not held reset by the reset pulse P4 of FIG. 2H between the times t_{63} and t_{64} , the voltages $+V_p$ and $+V_d$ are integrated by the integration circuit 3 between the times t_{58} and t_{64} and the integrated output E (hereinafter referred to as E_{64}) has a value given by the following equation at the time t_{64} .

$$E_{64} = +E_{58} - \frac{1}{RC} \int_{t_{58}}^{t_{64}} (V_p + V_d) dt \quad (25)$$

In this case, however, the voltages V_a to V_d are selected to satisfy the Equations (20a) to (20d) in relation to the voltage V_p , numbers such as "6," "10," "14" and "17" are set in the setting circuits 53a to 53d respectively and the time intervals between the times t_{32} and t_{42} , between t_{42} and t_{50} , between t_{50} and t_{58} and between t_{58} and t_{64} are set to be $10\tau_1$, $8\tau_1$, $8\tau_1$ and $6\tau_1$, respectively, as will become apparent from the following description. Accordingly, if the output $|-E_{58}|$ is equal to a maximum value of the output $|+E_{32}|$, the output E_{64} has the value "0."

40 Further, if the output L becomes "0" at a certain time t_a between the times t_{32} and t_{42} , only the output M_a becomes "1" between the times t_{32} and t_a , so that the voltages V_p and $-V_a$ are integrated between the times t_{32} and t_a and the integrated output E (hereinafter referred to as E_a) at the time t_a has a value given by the following equation and becomes zero.

$$E_a = +E_{32} - \frac{1}{RC} \int_{t_{32}}^{t_a} (V_p - V_a) dt = 0 \quad (26)$$

50 Thus, when the compared output Q has the value "0" at the time t_a , the output L has the value "0" after the time t_a . Thereafter, any of the outputs M_a to M_d does not become "1" after the time t_a , and hence any of the switches 59a to 59d is not closed after the time t_a . As a result of this, only the voltage $+V_p$ is integrated by the integration circuit 3 between the times t_a and t_{48} and the integrated output E at the time t_{48} has a value E_{48} given by the following equation.

$$-E_{48} = -\frac{1}{RC} \int_{t_a}^{t_{48}} V_p dt \quad (27)$$

65 Further, after the operation has thus been achieved until the time t_{48} , the output L from the zero level de-

pecting circuit 58 does not become "1" between the times t_{48} and t_{64} as previously described, so that any of the outputs M_a to M_d does not come to have the value "1" between the times t_{48} and t_{64} and any of the switches 60a to 60d is not closed. Accordingly, the 5 same integration as above described is achieved and the integrated output E at the time t_{56} has a value E_{56} given by the following Equation (28). If the output E_{56} at the time t_{56} is positive or zero, the output E obtained 10 at the time t_{60} has a value given by the following Equation (29a) or (29a') and if negative, the output E has a value E_{60} given by the following Equation (29b). Further, if the output E_{60} at the time t_{60} is positive or zero, the output E obtained at the time t_{62} has a value E_{60} given by the following Equation (30a) or (30a') and if 15 negative, the output E has a value E_{62} given by the following Equation (30b). Moreover, the output E obtained at the time t_{63} has a value E_{63} expressed by the following Equation (31a) or (31a') or (31b) according as the output E_{62} at the time t_{62} is positive or zero or 20 negative.

$$E_{56} = -E_{48} + \frac{1}{RC} \int_{t_{48}}^{t_{56}} V_p dt \quad (28) \quad 25$$

$$E_{60} = +E_{56} - \frac{1}{RC} \int_{t_{56}}^{t_{60}} V_p dt \quad (29a) \quad 30$$

$$-E_{60} = -\frac{1}{RC} \int_{t_{56}}^{t_{60}} V_p dt \quad (29a') \quad 35$$

$$E_{60} = -E_{56} + \frac{1}{RC} \int_{t_{56}}^{t_{60}} V_p dt \quad (29b) \quad 40$$

$$E_{62} = +E_{60} - \frac{1}{RC} \int_{t_{60}}^{t_{62}} V_p dt \quad (30a) \quad 45$$

$$-E_{62} = -\frac{1}{RC} \int_{t_{60}}^{t_{62}} V_p dt \quad (30a') \quad 55$$

$$E_{62} = -E_{60} + \frac{1}{RC} \int_{t_{60}}^{t_{62}} V_p dt \quad (30b) \quad 60$$

$$E_{63} = +E_{62} - \frac{1}{RC} \int_{t_{62}}^{t_{63}} V_p dt \quad (31a) \quad 65$$

$$-E_{63} = \frac{1}{RC} \int_{t_{62}}^{t_{63}} V_p dt \quad (31a')$$

$$E_{63} = -E_{62} + \frac{1}{RC} \int_{t_{62}}^{t_{63}} V_p dt \quad (31b)$$

In the case where the output L has the value "0" at a time t_b between the times t_{42} and t_{48} after the integrated output E_{42} of the Equation (22) has been obtained at the time t_{42} as above described, the voltages $+V_p$ and $-V_b$ are similarly integrated between the times t_{42} and t_b and the integrated output E (hereinafter referred to as E_b) at the time t_b has a value given by the following equation and is zero.

$$E_b = +E_{42} - \frac{1}{RC} \int_{t_{42}}^{t_b} (V_p - V_b) dt = 0 \quad (32)$$

When the output L has thus become "0" at the time t_b , the voltage $+V_p$ is integrated between the times t_b and t_{48} in the same manner as that in the foregoing and at the time t_{48} the output E is provided to have a value expressed by the following Equation (33).

$$-E_{48} = -\frac{1}{RC} \int_{t_b}^{t_{48}} V_p dt \quad (33)$$

After the operation has thus been carried out until the time t_{48} , the output E_{56} based on the Equation (28), the output E_{60} based on the Equation (29a), (29a') or (29b), the output E_{62} based on the equation (30a), (30a') or (30b) and the output E_{63} based on the Equation (31a), (31a') or (31b) are obtained at the times t_{56} , t_{60} , t_{62} and t_{63} , respectively in the same manner as that above described.

Further, after the integrated output E_{42} has been obtained at the time t_{42} as above described, if the output L has the value "0" at a time t_b' between the times t_{48} and t_{50} , the voltage $+V_p$ is similarly integrated between the times t_{42} and t_b' and the output voltage E (hereinafter referred to as E_b') at the time t_b' is provided to have a value given by the following equation which is zero.

$$E_b' = +E_{42} - \frac{1}{RC} \int_{t_{42}}^{t_b'} (V_p - V_b) dt = 0 \quad (34)$$

When the output L has thus become "1" at the time t_b' , the voltage $+V_p$ is likewise integrated between the times t_b' and t_{56} and the output E is provided to have a value given by the following Equation (35) at the time t_{56} .

$$-E_{56} = -\frac{1}{RC} \int_{t_b'}^{t_{56}} V_p dt \quad (35)$$

After the operation has thus proceeded to the time t_{56} , the outputs E_{60} , E_{62} and E_{63} are obtained at the times t_{60} , t_{62} and t_{63} , respectively based on the Equations (29b), (30a), (30a') or (30b) and (31a), (31a') or (31b) in the same manner as that above described.

In the event that the output L comes to have the value "0" at a time t_c between the times t_{50} and t_{56} after the output E_{50} at the time t_{50} has been obtained based on the Equation (23), the voltages $+V_p$ and $-V_c$ are integrated between the times t_{50} and t_c to provide the in-

tegrated output E of a value given by the following Equation (36) at the time t_c . In such a case, the voltage $+V_p$ is integrated between the times t_c and t_{56} to provide the output $-E_{56}$ given by the following Equation (37) at the time t_{56} and thereafter the outputs E_{60} , E_{62} and E_{63} are obtained at the times t_{60} , t_{62} and t_{63} , respectively based on the equations (29b), (30a), (30a') or (30b) and (31a), (31a') or (31b) as is the case with the foregoing.

$$E_c = +E_{50} - \frac{1}{RC} \int_{t_{50}}^{t_c} (V_p - V_c) dt = 0 \quad (36)$$

$$-E_{56} = -\frac{1}{RC} \int_{t_c}^{t_{56}} V_p dt \quad (37)$$

Where the output L becomes "0" at a time t_c' between the times t_{56} and t_{58} after the output E_{50} at the time t_{50} has been obtained based on the Equation (23) as above described, the voltages $+V_p$ and $-V_c$ are integrated between the times t_{50} and t_c' to provide the output E having a value given by the following Equation (38) at the time t_c' and then the voltage $+V_p$ is integrated between the times t_c' and t_{60} to provide an output $-E_{60}$ given by the following Equation (39) at the time t_{60} . Thereafter, outputs E_{62} and E_{63} based on the equations (30b) and (31a), (31a') or (31b) are similarly obtained at the times t_{62} and t_{63} , respectively.

$$E_c' = +E_{50} - \frac{1}{RC} \int_{t_{50}}^{t_c'} (V_p - V_c) dt = 0 \quad (38)$$

$$-E_{60} = -\frac{1}{RC} \int_{t_c'}^{t_{60}} V_p dt \quad (39)$$

Where the output L has the value "0" at a time t_d between the times t_{58} and t_{60} after the output E_{58} at the time t_{58} has been obtained based on the Equation (24) as above described, an output E_d is obtained at the time t_d based on the following Equation (40), an output E_{60} at the time t_{60} based on the following Equation (41), the output E_{62} at the time t_{62} based on the Equation (32b) and the output E_{63} at the time t_{63} based on the Equation (31a), (31a') or (31b). If the output E has the value "0" at the time t_d' between the times t_{60} and t_{62} after the output E_{58} has been obtained based on the Equation (24) at the time t_{58} as above described, an output E_d' based on the following Equation (42), an output E_{62} based on the following Equation (43) and the output E_{63} based on the equation (31b) are obtained at the times t_d' , t_{62} and t_{63} , respectively. If the output L becomes "0" at a time t_d'' between the times t_{62} and t_{63} after the output E_{58} based on the Equation (24) has been obtained from the time t_{58} , outputs E_d'' and $-E_{63}$ given by the following Equations (44) and (45) are obtained at the times t_d'' and t_{63} , respectively.

$$E_d = E_{58} - \frac{1}{RC} \int_{t_{58}}^{t_d} (V_p + V_d) dt = 0 \quad (40)$$

$$-E_{60} = -\frac{1}{RC} \int_{t_d}^{t_{60}} V_p dt \quad (41)$$

$$E_d' = E_{58} - \frac{1}{RC} \int_{t_{58}}^{t_d'} (V_p + V_d) dt = 0 \quad (42)$$

$$-E_{62} = -\frac{1}{RC} \int_{t_d}^{t_{62}} V_p dt \quad (43)$$

$$E_d'' = E_{58} - \frac{1}{RC} \int_{t_{58}}^{t_d''} (V_p + V_d) dt = 0 \quad (44)$$

$$-E_{63} = \frac{1}{RC} \int_{t_d''}^{t_{63}} V_p dt \quad (45)$$

After the time t_{64} , the times t_{108} , t_{114} , t_{122} and t_{128} ; t_{172} , t_{178} , t_{186} and t_{198} ... correspond to t_{42} , t_{50} , t_{58} and t_{64} and the same operations as those above described are achieved.

In the periods during which the output R3 from the flip-flop circuit 13 has the value "0," the pulse train "CP1'" are derived from the "and" gate circuit 37 as is the case with the foregoing example and the pulses of the pulse train "CP1'" are counted by the counter 42 and the number of pulses counted by the counter 42 is indicated by the indicator 43 as is the case with the foregoing example.

Accordingly, the number of pulses counted by the counter 42 is obtained in such a form that the integrated output $+E_{32}$ of the Equation (21) has been corrected according to its value. Namely, in the example of FIG. 1, the input voltage V_i is constant and the input voltage V_d and the counting number N of the counter 42 bear the relationship given by the Equation (11) and indicated by I in FIG. 3. In the example of FIG. 4, in the range of $N = 0$ to $N = (6-1) = 5$ the value of the input voltage V_d is obtained with the relationship given by the following Equation (46) and indicated by a line II_a in FIG. 3.

$$|V_d| = \frac{1}{4}N \quad (46)$$

In the range of $N = 5$ to $N = (10-1) = 9$ the value of the input voltage V_d is obtained with the relationship given by the following Equation (47) and indicated by a line II_b in FIG. 3.

$$|V_d| = \frac{1}{2}N - (\frac{1}{2} \times 5 - \frac{1}{4} \times 5) = \frac{1}{2}N - 5/4 \quad (47)$$

In the range of $N = 9$ to $N = (14-1) = 13$ the value of the input voltage V_d is obtained with the relationship given by the following Equation (48) and indicated by a line II_c in FIG. 3.

$$|V_d| = \frac{3}{4}N - \{ \frac{3}{4} \times 9 - (\frac{1}{2} \times 9 - 4/5) \} = \frac{3}{4}N - 7/2 \quad (48)$$

In the range of $N = 13$ to $N = (17-1) = 16$ the value of the input voltage V_I is obtained with the relationship given by the following Equation (49) and indicated by a line II_d in FIG. 3.

$$|V_I| = 39/12N - \{39/12 \times 13 - (3/4 \times 13 - 7/2)\} = 39/12N - 36 \quad (49)$$

This will become more apparent from the following concrete example.

Let it be assumed that the input voltage $-V_I$ is constant and that the output voltage $+E_{32}$ expressed by the Equation (21) is equal to the value in the case where the indication “-16V” is provided in the example of FIG. 1. In such a case, the integrated output E increases in the positive direction from the time t_0 to reach a point $X7_0$ at the time t_{32} at which the output voltage $+E_{32-7}$ based on the Equation (21) is obtained, as indicated by a line $U7_0$ in FIG. 2T, from thence the output E increases in the negative direction to reach a point $X7_1$ at the time t_{42} at which the output $+E_{42-7}$ based on the Equation (22) is obtained, as indicated by a line $U7_1$, from thence the output E increases in the negative direction to reach a point $X7_2$ at the time t_{50} at which the output $+E_{50-7}$ based on the Equation (23) is obtained, as indicated by a line $U7_2$, from thence the output E increases in the negative direction to reach a point $X7_3$ at the time t_{58} at which the output $+E_{58-7}$ based on the Equation (24) is obtained, as indicated by a line $U7_3$, and from thence the output E further increases in the negative direction to reach a point $X7_4$ at the time t_{64} at which the output $E_{64-7} = 0$ based on the Equation (25) is obtained, as indicated by a line $U7_4$, unless the switch 9 of the integration circuit 3 is closed between the times t_{63} and t_{64} . In this case, the compared output Q, the output R3 from the flip-flop circuit 13, the output R4 from the flip-flop circuit 14 and the pulse train CP1' from the “and” gate circuit 37 are obtained as shown in FIGS. 2K₇, 2L₇, 2N₇ and 2M₇. Further, the output L from the zero level detecting circuit 58 and the outputs M_a to M_d from the “and” gate circuits 57a to 57d are obtained as depicted in FIGS. 2V₇ and 2Ua₇ to 2Ud₇, respectively.

Consequently, the counter 42 counts 16 pulses in all between the times t_0 and t_{64} and the indicator 43 provides an indication “-16V.” Also between the times t_{64} and t_{128} , between t_{128} and t_{192} , . . . the indicator 43 provides the indication “-16V.” This implies that the input voltage $-V_I$ has been corrected from its original value (although the values are equal to each other in the present example) for the following reason. Namely, in the present example the voltage $+E_{32}$ is the same as that in the case where the indication “-16V” is obtained in the example of FIG. 1 and if the value “16” being indicated is substituted for the value of N in the Equation (49), it follows that $V_I = 0$.

Assuming that the input voltage V_I is a negative constant voltage and that the output voltage $+E_{32}$ expressed by the Equation (21) is one-fourth times smaller than that the indication “-16V” is obtained in the example of FIG. 1, the integrated output E increases in the positive direction from the time t_0 to reach a point $X8_0$ at the time t_{32} at which the output $+E_{32-8}$ based on the Equation (21) is obtained, as indicated by a line $U8_0$, from thence the output E increases in the negative direction to reach a point $X8_1$ at the

time t_{42} at which the output $+E_{42-8}$ based on the Equation (22) is obtained, as indicated by a line $U8_1$, from thence the output E increases in the negative direction to reach a point $X8_2$ at the time t_{50} at which the output E_{50-8} based on the Equation (25) is obtained, as indicated by a line $U8_2$, from thence the output E increases in the negative direction to reach a point $X8_3$ (the point of the time t_c) at which the output $E_{c-8} = 0$ based on the Equation (36) is obtained, as indicated by a line $U8_3$, from thence the output E increases in the negative direction to reach a point $X8_4$ at the time t_{58} at which the output $-E_{56-8}$ based on the Equation (37) is obtained, as indicated by a line $U8_4$, from thence the output E increases in the positive direction to reach a point $X8_5$ at the time t_{60} at which the output E_{60-8} (the value of “0” in the present example) based on the Equation (29b) is obtained, as indicated by a line $U8_5$, from thence the output E increases in the negative direction to reach a point $X8_6$ at the time t_{62} at which the output $-E_{62-8}$ based on the Equation (30a') is obtained, as indicated by a line $U8_6$, and from thence the output E increases in the positive direction to reach a point $X8_7$ at the time t_{63} at which the output $+E_{63-8}$ based on the Equation (31b) is obtained, as indicated by a line $U8_7$ and the output E has the value “0” between the times t_{63} and t_{64} . In this case, the compared output Q, the output R3 from the flip-flop circuit 13, the output R4 from the flip-flop circuit 14 and the pulse train CP1' from the “and” gate circuit 37 are obtained as illustrated in FIGS. 2K₈, 2L₈, 2N₈ and 2M₈, respectively. Further, the output L from the zero level detecting circuit 58 and the outputs M_a to M_d from the “and” gate circuits 57a to 57d are obtained as depicted in FIGS. 2V₈ and 2Ua₈ to 2Ud₈, respectively.

Consequently, the counter 42 counts 10 pulses in all between the times t_0 and t_{64} and the indicator 43 provides an indication “-10V.” Also between the times t_{64} and t_{128} , between t_{128} and t_{192} , . . . the indication “-10V” is similarly provided by the indicator 43. In the present example, the voltage $+E_{32}$ is one-fourth times lower than that in the case where the indication “-16V” is provided in FIG. 1 and if the value of “10” being indicated is substituted for the value of N in the Equation (48), it follows that $V_I = 4$. Accordingly, the indication “-10V” implies that the input voltage $-V_I$ has been corrected from its original value.

Namely, in the example of FIG. 1 the value of the input voltage $-V_I$ is indicated as “-4V,” while in the example of FIG. 4 it is indicated as “-10V” after corrected.

The foregoing description has been made in connection with only two examples of this invention in which the value of the input voltage $-V_I$ is constant but even if the value of the input voltage V_I is positive or negative and even if its absolute value is any other than the aforementioned, a digital value representative of the corrected input voltage V_I can similarly be obtained. However, in the case of the input voltage V_I such that the value N obtained by putting a numerical value in V_I of the aforesaid Equations (46) to (49) is not an integer, the value N based on the Equations (46) to (49) is obtained in such a form that fractions of 5 and over are counted as a unit and the rest is cut away under the decimal point.

Thus, in the present example, it is possible to obtain the digital value N corresponding to the value of the input voltage V_I but corrected in accordance therewith

and it will be seen that the relationship between V_i and N depends on the broken line characteristic shown in FIG. 3.

The foregoing examples are intended as being illustrative and not as limiting the present invention specifically thereto. For example, the inverter circuit 41 may be omitted, in which case an output R3' similar to that derived from the inverter circuit 41 is obtained at the "not" output terminal n (not shown) of the flip-flop circuit 13. In the foregoing the time for integration (referred to as T_c) of the input voltage V_i is the time $\tau_1 \cdot 32$ between the times t_0 and t_{32} but the present invention is also applicable to the case where T_c uses $\beta \tau_1 \cdot 32$, β being a constant. In the foregoing the periods of time for sequential integration of the reference voltage are taken as $T_1, T_2, \dots$ and the integration is achieved using T_1 as the reference therefor and with the relationship: $T_2 = T_1/2, T_3 = T_1/4, T_4 = T_1/8, T_5 = T_1/16$ but if $j = 2, 3, \dots, n$, the value n can be set at a desired integer with a relationship $T_j = T_1/2^{j-1}$. In the case of the broken line characteristic, the number of its broken points can be set as desired and the values of the broken points, that is, the polarities and values of the voltages V_a to V_d can also be set at will and, further, the values of the resistors 6 and 61 can be selected different from each other.

It will be apparent that many modifications and variations may be effected without departing from the scope of the novel concepts of this invention.

I claim as my invention:

1. An analog to digital converter comprising in combination:

- an integrating amplifier means,
- a source of clock pulses,
- a timing signal generator that produces timing pulses that define for each conversion cycle a series of time intervals the first and second of which are selected portions of a conversion cycle and each of the remainder of which is half the preceding interval,
- means for applying a signal of unknown amplitude and polarity to said integrating amplifier only during the first timing interval of each conversion cycle to obtain an amplifier output representative of the unknown signal,

- means for applying signals of known amplitude and polarity to said amplifier during the second and each of the following time intervals to reduce the amplifier output toward zero, and
- means for counting the clock pulses during those time intervals following the second interval and during only those time intervals in which the polarity of the amplifier output at the start of the interval is the same as the polarity of the amplifier output at the end of said first time interval.
- An analog to digital converter according to claim 1 in which said timing signal generator is controlled by the clock pulse generator and provides timing signals marking the beginning and end of each of said time intervals and of the conversion cycle.
- In an analog to digital converter according to claim 1, a flip-flop circuit, means responsive to the polarity of the amplifier output for conditioning the flip-flop circuit, means for triggering the flip-flop circuit from said timing signal generator, and means responsive to the flip-flop circuit for selecting the polarity of the known amplitude signals for each time interval.
- In an analog-to-digital converter according to claim 1, a digital indicator and means for supplying the digital indicator with a counted output from the pulse counting means and in which a digital value is indicated by the digital indicator corresponding to the integrated output at the time of completion of integration of the analog input signal with the integrating means.
- In an analog to digital converter according to claim 1, a source of supplementary signals of known amplitude and polarity, means connected to said source for applying the supplementary signals to said amplifier during a time interval starting with the start of the second time interval and terminating upon a reversal of the polarity of the output of the amplifier.
- In an analog to digital converter according to claim 1 at least one source supplying a supplementary signal of known amplitude and polarity, presettable counting means connected to indicate selected counts of the series of clock pulses of each conversion cycle, and switch means arranged to connect said supplementary source to the amplifier during a time interval determined at least in part by the accumulation of selected counts in said presettable counting means.
